CLAIM

The ornamental design for a valve controller for an oil pressure valve, as shown and described.

(**) Term: **14 Years**

DESCRIPTION

(21) Appl. No.: **29/525,933**

FIG. 1 is a perspective view of a valve controller for an oil pressure valve, showing my new design;

(22) Filed: **May 5, 2015**

FIG. 2 is another perspective view thereof;

(51) LOC (10) Cl. 23-01

FIG. 3 is a front view thereof;

(52) U.S. Cl.

FIG. 4 is rear front view thereof;

USPC **D23/233**

FIG. 5 is a left side view thereof;

(58) **Field of Classification Search**

FIG. 6 is a right side view thereof;

USPC D23/233-249; 137/487.5, 12, 14, 554,
137/556, 553, 315.35, 636.2, 270;
251/129.12, 129.02, 129.03, 291, 292,
251/128, 129.11, 304, 129.13, 111, 93, 101,
251/97, 235; 74/491

FIG. 7 is a top view thereof;

CPC F16K 31/0675; F16K 31/00; F16K 31/12
See application file for complete search history.

FIG. 8 is a bottom view thereof;

(56) **References Cited**

FIG. 9 is an operational perspective view thereof showing the valve controller for an oil pressure valve mounted on a single oil pressure valve assembly;

U.S. PATENT DOCUMENTS

FIG. 10 is another operational perspective view thereof showing the valve controller for an oil pressure valve mounted on a dual oil pressure valve assembly; and,

3,677,281 A * 7/1972 Tennis 137/270
3,831,633 A * 8/1974 Comer 137/636.2
3,943,791 A * 3/1976 Casey 137/636.2
4,028,958 A * 6/1977 Schuermann et al. 137/636.2
5,062,516 A * 11/1991 Prince 477/98

FIG. 11 is still another operational perspective view thereof showing the valve controller for an oil pressure valve mounted on a triple oil pressure valve assembly.

The broken lines in the drawings are included for the purpose of illustrating portions of the valve controller for an oil pressure valve and form no part of the claimed design.
